UNITED STATES PATENT OFFICE.

WALTER F. ROLSTON, OF ROCKFORD, ILLINOIS, ASSIGNOR OF ONE-HALF TO WILLIAM H. ZIOCK, OF ROCKFORD, ILLINOIS.

NEEDLE-OPERATING MECHANISM FOR STRAIGHT KNITTING MACHINES.

Application filed December 21, 1923. Serial No. 681,988.

This invention relates to straight knitting machines of the parallel row type, such as disclosed in U. S. Patent No. 616,600 to William Worth Burson, and has more particular reference to the needle-operating mechanism, especially in respect to advancing and retracting the needles and control thereof.

One of the primary objects of my invention is to improve machines of this type so that finer and more delicate yarns may be used without stressing the yarn fibres or impairing their elasticity; and consequently, to enable the knitting of finer fabrics. I have also aimed to obtain greater precision and uniformity in the knitting, and to produce a better quality of knitting than has heretofore been possible with such machines.

Another object is to improve the construction and operation of machines of this type with the view to knitting easier, with less strain and tension on the yarn and less friction on the needles and co-operating parts. As a result, the needles are more accurately and positively controlled, there is less wear on the parts and less power required for their operation, and the life of the mechanism is increased. By relieving the strain and tension on the yarn, and for other reasons which will be apparent from the following disclosure, there is no tendency or cause to impair, stress or break the yarn at any time while knitting a fabric, or afterward by stretching it. Furthermore, the yarn will retain its original elasticity so that, in the case of fabrics such as stockings, they will retain their form and hold to the shape of the leg.

Another object is to provide improved mechanism whereby to permit of abrupt changes in tension while knitting, as for example when changing from relatively tight to loose stitches in knitting the foot and upper portions, respectively, in a stocking, and when knitting a "slack course" at the top of a stocking as an identification and guide for sewing on a rib top; and it is an object to make these changes in tension without breaking the yarn or impairing its strength or elasticity.

Another object is to improve the knitting action in machines of this type, especially at the critical time of forming the loop.

A further object is to improve the construction and operation of the needle-re-

tracting cams with the view to reducing wear in the slide mountings of these cams, and consequently remedying certain inaccuracies in knitting and non-uniformity of product heretofore resulting from uneven 60 and unusual wear in such mountings.

Other objects and attendant advantages will be appreciated by those skilled in this art as the invention becomes better understood by reference to the following description when considered in connection with the accompanying drawings, in which—

Figure 1 is a vertical sectional view transversely of one of the needle beds of a parallel-row straight knitting machine, embodying my invention;

Fig. 2 is an edge view of one of the needle cam slides;

Fig. 3 is a bottom view of the cam slide shown in Fig. 2, and showing a number of 75 needle jack lugs in section;

Fig. 4 is a similar bottom view of the cam slide with the underlying parts shown in dotted lines; and

Figs. 5 and 6 are detail perspective views 80 of one of the retracting cams and its sectional carrier.

While my improvements are applicable to any parallel-row straight knitting machine, I have for purpose of illustration merely, 85 shown them as embodied in a Burson type machine, and more particularly, in one embodying certain other improvements forming the subject matter of my co-pending application, Serial No. 76,142.

In Fig. 1, I have shown in vertical section the needle bed and needle-operating parts at one side of the center line indicated by the reference numeral 6, it being understood that this mechanism is duplicated on 95 the opposite side of said center line. The bed frame 7 carries a bed plate 8 which has upstanding portions 9 and 11 reaching lengthwise of the bed and being slotted crosswise thereof in comb-like fashion for 100 the reception of sheet metal division plates designated generally by 12. These division plates defined in length by inner and outer edges 13 and 14, respectively, are further supported and held in alignment at 105 their rear ends by a bar 15 and have upstanding portions 16 confined in comb-like slots 17 in a retaining bar 18 which is held in rigid relative relation to the said frame.

In the space between each two adjoining 110

division plates is located a needle support 19, a needle 20, a jack 21, a jack housing 22, a pattern lever 23, and a tension or filler spring 24, these reference numerals being 5 generally applied. It is well understood in this art that the parts for supporting and operating each needle are duplicated; consequently, a detailed description of but one of such parts for operating a single needle 10 will be given, although in referring to the knitting operation, the needles will be referred to collectively. The needle support 19 has an end portion 25 reaching into the throat of the machine and provides an uninterrupted bearing surface on which the needle 15 is adapted to slide back and forth. Stationary rods 26 and 27 passing through the needle support and jack housings respectively, and also through the division plates, 20 serve to further hold these parts in the desired relative relation.

The spring 24 for holding the needle down on its supporting part may be of any suitable construction, but I prefer to employ one 25 which is located in a stationary position and is adapted to be removed therefrom through the throat opening when removing the needle and jack as is sometimes required for inspection and repair of these parts. In the 30 present instance, the spring has a shank 28 provided with a lug 29 seated in a slot in the sinker bed 31, it being manifest that by depressing the shank the lug 29 may be withdrawn from its retaining slot, permitting 35 withdrawal of the spring through the throat. This spring is exceptionally light for machines of this type so as to impose less than the usual pressure on the needle, for reasons which will be explained more fully 40 hereinafter.

The usual sinkers 32 held in position on the sinker bed by the sinker cap 33 are adapted to be advanced and retracted by the sinker cam bar 34 in proper timed relation with 45 the advancing and retracting of the needles as is well understood in this art and as will be more fully described hereinafter.

The jack housing 22 pivotally supported at its inner end on the rod 27 is adapted to 50 be swung on such pivot for raising and lowering the jack lug 35 into and out of operative relation to the cams which are adapted for engaging such lug for advancing and retracting the jack and consequently its needle. 55 The jack has a hooked inner end, the recess 36 of which receives the upturned end 37 of the needle. The jack housing or support may be raised and lowered by any suitable means, such for example as the pattern lever 23 which is pivoted on a rod 38 carried by the division plates 12. This lever has follower projections 39 and 41 which ride on the periphery of pattern plates 42 and 43 respectively. These pattern plates, carried 60 by the pattern cylinder, are revolved in a

counter-clockwise direction viewing Fig. 1, in step-by-step movements and are so shaped as to raise and lower the jacks for bringing a greater or less number of needles into action, thereby determining the shape of the 70 fabric. That is, when the jack housing is in the raised position shown in Fig. 1, the lug 35 on the jack will be positioned in the path of the cams which will be presently described, so that when said cams are reciprocated, 75 they will engage such lug and advance and retract the jack and its needle at predetermined times and in timed relation with the operation of the sinkers and yarn carrier. Such operation of latch needles 80 by cams under control of a pattern cylinder is well understood in this art; and it is not deemed necessary to describe in detail the complete knitting action. While the construction so far described embodies certain 85 improvements claimed in my copending application above mentioned, nevertheless, in so far as my present invention is concerned, the usual Burson or equivalent construction of such parts may be used. However, I prefer 90 that the filler spring, as regards certain phases of my invention, shall be exceptionally light, as will be presently explained.

My invention contemplates the provision of an improved mechanism for operating 95 the needles with the view of accomplishing the objects above mentioned. My improvements are therefore, primarily embodied in the construction of the needle operating cams. Such cams are carried by a cam bar 10 slide 44 mounted in suitable bearings and adapted to be reciprocated by means of a cross head or bar (not shown) to which the sinker cam bar 34 and the yarn-carrier bar (not shown) are likewise attached. The 10 cam bar slide carries on its under side, a pair of retracting cams also known as stitch or wing cams 45 and 46 and an advance cam 47 also known as a center cam. Figs. 3 and 4 show these cams as they appear 11 looking at the underside of the cam bar slide, the upper and lower edges of the cam bar slide being designated by 48 and 49 respectively. The center cam having needle advancing faces 51, is attached to a bar 52 11 through means of an attaching part 53 extending through an opening 50 in the slide; and the bar 52 travels with the slide 44 and is equipped with an eccentric cam 54 adapted to be operated at predetermined times by 12 mechanism, not shown, for raising and lowering the center or advance cam. The advance cam when lowered is in its operative position for engaging any of the jack lugs which have been raised and advancing them 12 and their needles; and when raised, the advance cam passes idly over the jack lugs.

Each retracting cam is mounted on the cam bar slide with capacity for adjustment 13 and movement thereon in a plane parallel

with its needle-retracting face 55. Such adjustment is desired for the purpose of changing the tension of the knitting, that is, to knit tight or loose, as is well understood in this art; and the present invention provides for an additional movement of the retracting cams in this plane, or an equivalent action, whereby to relieve the retracting cam at certain times to prevent imposing additional tension on the yarn, as will be presently apparent. In the preferred embodiment of my invention, I provide a sectional carrier for each retracting cam. As shown in Figs. 5 and 6, these carrier sections are designated generally by 56 and 57, each retracting cam being fixed to a cam-carrier section 56. The cam-carriers 56 and 57 are held in position on the underside of the cam bar slide by guide plates 58 secured by suitable fastening means to said slide. The bearing surfaces between the cam-carrier sections and the guide plates permit movement of said sections in a plane parallel with the cam face 55 and are of an improved construction for preventing undue wear and tilting of the cam laterally as with respect to the plane of movement as a consequence of such wear. To this end, I have provided bearings in the form of interlocking joints, between said cam-carrier sections and the guide plates, these interlocking joints being rebated and tongued as shown plainly in Figs. 2, 5 and 6, thus providing end bearing faces 59 and an intermediate bearing face 61 between the overlapping and interlocking tongued portions of each joint. The advantages of this construction will be pointed out later. Each cam-carrier section 57 has rigidly attached thereto, a lifter cam 62, the function of which will be presently described. To each cam-carrier section 57 is also rigidly attached as shown in Fig. 5, a part 63 disposed in a slot 60 in the slide 44 for movement lengthwise therein. Each part 63 carries an upwardly projecting stud 64, Fig. 1, on which is mounted a guide bar 65 in turn disposed in the channel of an adjuster bar 66. This adjuster bar reaches substantially throughout the length of the bed and is adapted to be moved up and down in the inclined plane of the cam bar slide for the purpose of changing the tension of the knitting, that is, for knitting tight or loose, as explained in the above mentioned patent. In the present case, the bar 66 is adjusted by means of tension brackets 67 mounted on a shaft 68, each bracket having at its lower end a plurality of screws resting on a plurality of follower levers 69 which ride on tension control plates on the pattern cylinder and are individually operable for changing tension. When the followers are lowered by the control plates, the adjuster bar will be moved upwardly, thereby correspondingly moving the cam-carrier sections 56 and 57 and the retracting cams, the result being that a tighter fabric will be produced. It follows that by raising and lowering the adjuster bar in its inclined plane, the knitting will be relatively loose or tight, according to the extent of the adjustment. This tension-changing device is known to the prior art.

It will be observed that each cam-carrier section 56 is yieldingly held down against its companion section 57 by means of a contractile spring 71, at present attached at opposite ends to the slide 44 and to the retracting cam fixed to said carrier section 56, so that both cam-carrier sections move as a unit when adjusted for changing the tension, that the carrier section 56 and its retracting cam are movable on the guide plates 58 away from the carrier section 57 against the pressure of the spring 71 and are therefore, independently movable with respect to said section 57, and that the spring 71 is disposed in the plane of such movement and is of such tension as to impart very little resistance to said independent cam movement but to positively return and hold the cam and its carrier section in the normal operative position against the carrier section 57 when opposition to the spring pressure is relieved. The foregoing construction is important, especially in conjunction with the use of comparatively light filler springs on the needles, for reasons which will be apparent upon considering the knitting action.

Machines of this type are designed for knitting back and forth on either bed, the needles in action being controlled by raising and lowering the needle jacks by the pattern cylinder, according to the shape and nature of the fabric desired. When knitting a stocking, it is desired to knit back and forth on each bed for knitting the sole portion of the foot with a comparatively heavy yarn and the upper portion with a lighter yarn. The knitting action may be followed by reference to Fig. 3. Assuming that the cam-carrier slide 44 is traveling toward the right hand side of the sheet, the needles of the jacks 72 remain quiescent, with held loops, until advanced by the leading face 51 of the advancer cam 47, the needles at this stage being indicated by 73. As the cam bar slide progresses in its stroke, the needles will be retracted by the face 55 of the retracting cam 46, and will take the yarn laid in the needle hooks by the yarn-carrier (not shown). As each needle is retracted the stitch or loop, that is held thereon will close the latch, and the needle will draw a new loop through the old one, which slips over the closed latch and is drawn down by the fabric onto the new loop. In forming the new loop, the yarn is drawn by

the needle between two adjacent sinkers and held there. It will be here noted that the retracting face 55 of each retracting cam has an end 74 projecting below its face 75, the purpose of which is to draw the loop down to its greatest length and then to relieve the loop by permitting the needles to slightly advance to the extent determined by the cam face 75. Thus when drawing a loop, new yarn is taken from the yarn-carrier and as the loop is drawn down between the sinkers by the needle of the jack 76, some additional yarn is borrowed or drawn from the preceding loop (on the needle of the jack 77), the needle of which is slightly advanced, as mentioned, to aid in giving this yarn and to relieve its loop from stress or tension which would otherwise be imposed on this loop by the forming of the succeeding loop. It will be here noted that each filler spring 24 imposes certain friction on its needle and that in prior machines it has been necessary to employ a comparatively heavy spring in order to hold the needles from advancing prematurely when entering the cam way in front of the leading advancing cam face 51, and "knitting across". This heavy pressure caused excessive wear on the needles and their supports, and required greater power consumption. The total spring pressure on a bed is in some instances so great as to distort the bed structure, with consequent injuries. Furthermore, it is difficult in practice to obtain a satisfactory degree of uniformity of such needle pressure when comparatively heavy spring pressure is required, with the result that any relatively lighter spring will produce a tighter wale than the adjacent wales, thereby marring the uniformity of the knitting. According to the present invention, I employ a comparatively light filler spring so that these objectionable features of prior constructions in this regard are obviated. Furthermore, returning to the point in the knitting in which the needle advances slightly after being drawn down to its extreme position, it will be observed that with a light spring pressure on the needle, the needle will be immediately advanced merely by the pull of the yarn forming the new or succeeding loop, instead of remaining in the extreme retracted position until positively advanced by the follower cam 62 or until such advancing movement is transmitted to the needle by such cam after a slight interval, due to wear or play in the connection between the jack and the needle. In prior constructions requiring means such as a cam for positively advancing the needle after it has been drawn down to the final point in forming the stitch, as performed by the cam end 74 in the present case and in which the heavier needle springs are required to prevent knitting across, such advancing cam,

corresponding in the present case to the cam surface engaging the jack butt 76, becomes worn and fails to return the needles to the desired position, with the result that with variations in pressure of these heavier springs there will be a slight variation in the length of the loops with the result that the knitting will not be uniform. According to the present invention employing a comparatively light spring pressure on the needles a certain degree of tension is relieved at the critical time of forming the loop or stitch, which makes for easier knitting and imposes less strain on the yarn, this being an important factor enabling uniform knitting with fine yarns on this type of machine without danger of "knitting across".

Another objection to prior machines is that an additional pull or tension will be imposed on each held loop, at the time the pointed end 74 of the leading retracting cam 45 (referring to Fig. 2) passes over the jack of such held loop. In said prior machines the point 74 being relatively rigid when advancing, the jack lugs are compelled to ride under said point, thereby stretching each loop. This stretching of the loop is decidedly objectionable because it not only impairs the strength of the yarn but sometimes breaks the yarn. Consequently when the finished article is stretched in use, the weakened loops frequently break. Also, the stressing takes a certain amount of elasticity from the yarn, so that the knitted fabric has not the desired life, and in the case of knit stockings, will not fit as well, nor have the life of stockings knit without this stressing. By my invention, there is no stressing of the yarn fibres and the yarn retains its natural elasticity. To this end the leading retracting cam 45 yields (as shown in Fig. 2) by reason of the pressure of the jack lug against the pointed end 74 of the cam. The pressure required for thus displacing the cam 45 is very small and not sufficient to retract the needles; and inasmuch as the cam passes very rapidly along the needle jacks, said cam is held in this displaced position until all of the raised jack lugs have been passed. By reason of this yielding action of the leading retracting cam or of relieving its point 74 so as not to advance the needles and stress the loops the needles are not subjected to such action as will cause them to "knit across" as described above and as a consequence a much lighter spring pressure or tension may be imposed on each needle. As a result of this cam yielding action and the use of the comparatively lighter spring pressure on the needles I am enabled to knit with finer grades of yarn without impairing their strength or elasticity, and to produce a more uniform fabric. Another important advantage is that the knitting action is

made easier and there is less wear and friction on the needles and cooperating parts. The cam 46 functions in the same way on the return stroke, that is, the cam 46 is displaced and the cam 45 is drawn back to its normal position by the spring 71 and will be maintained in such position because the pressure of the jack lugs against the cams is crosswise of the plane in which the cam is movable.

Another advantage of the foregoing construction is that abrupt changes may be made in the tension as when changing from fine or light yarns to coarse or heavier yarns, or when changing from relatively tight to loose knitting, without stressing or breaking the loops held on the needles and without distorting the fabric. This is especially desirable for the purpose of knitting a slack course, that is, an exceptionally loose course. For example, it is sometimes desired to knit a loose course near the top of a stocking as a guide when transferring the stocking to a looper or other knitting machine for sewing on a ribbed top. In such case, when the tension is changed from the normal knitting to a comparatively loose course by means of the tension changing mechanism above described, the retracting cams will be simultaneously lowered so that a loop of the desired length will be drawn. With prior machines of this type, it was impossible to knit the desired slack course because the jack lugs upon encountering the projecting point 74 on the leading cam would be retracted thereby to the stitch-forming level of the new slack course stitch to be knit with the result that the held loops would be stretched and broken. With my construction, however, the leading cam is displaced as above described, thereby permitting the slack course to be knit as any other. One or more slack courses of this kind may be desired for other reasons, or for example, in the knitting of any fabric as a guide for turning a welt, or as part of a design. And, in the case of changing yarns and tension as when knitting a stocking, a change is made from a fine or light yarn (which is knit relatively tight) to a coarse or heavier yarn (knit looser). In such case, in prior machines of this type the relatively tight loops held on the needles will be stretched to a greater degree than usual by the leading retracting cam as above pointed out, thereby stressing and possibly breaking such held loops and distorting the adjacent courses of knitting, whereas with my improvements, the leading retracting cam is displaced so as not to disturb the held loops or in any way interfere with the preceding courses of knitting.

Still another advantage of my improvements affecting the knitting operation is ob-

tained from the construction and mounting of the retracting cams. As above described, the carrier sections for these cams are mounted to slide on ways in the form of interlocked joints. In prior machines, the practice was to simply rebate the cam carrier and provide guide plates fitting under the rebated edges so as to hold the cam-carriers in position on the underside of the cam bar slide with capacity for adjustment lengthwise of the ways for changing tension. As a consequence of this construction, the continual pressure by the jack lugs against the needle retracting faces caused the bearing faces to wear unevenly and the retracting cams to be tilted slightly upwardly at the leading end, thereby lowering the end portion of the cam face 75 remote from its pointed end 74. This caused the lower cam face 75 to comb the held loops by reason of the depressing action on the jack lugs, which was obviously undesirable. This wear developed in such machines in spite of accuracy in the manufacture of such parts and of using case-hardened steel parts; and the cost of manufacturing such parts was high due to distortion from hardening and to the necessary refinishing operations. According to my invention, the cam-carrier parts and their guide plates may be made of cast iron, thus materially reducing the cost of manufacture, and the interlocking joints afford increased bearing surface, also the overlapping interlocking portions cause the lateral pressure or thrust from the cams resulting from the needle retracting action, to be so distributed and resisted from opposed sides as to have a negligible affect on such bearing surfaces. Thus precision in operation of the retracting cams and consequently in the uniformity and quality of the resultant knitting are obtained.

It is believed that the foregoing conveys a clear understanding of the objects prefaced above. And it will be obvious to those skilled in the art that the details of structure and relative arrangement as herein shown might be variously modified without involving any substantial change in the structure or its principle of operation. It should therefore, be understood that I do not limit myself to the exact construction herein shown and described, but reserve the right to make such variations therein as fairly fall within the spirit and scope of the invention.

I claim:

1. In a straight knitting machine, means whereby each retracting cam when leading will yield so as not to stress the held loops.
2. In a straight knitting machine, in combination, the needles, the stitch-forming cams including retracting cams and an advancing cam, means for simultaneously adjusting both retracting cams for changing

the tension, and means whereby each retracting cam will yield when leading so as not to stress the held loops.

3. In a straight knitting machine, in combination, the needle cam slide, the stitch-forming cams thereon including the retracting cams, and means permitting each retracting cam to yield from its normal position when leading so as not to retract the needles and stress the held loops.

4. In a straight knitting machine, in combination, the needles, the needle cam slide, the retracting cams on each slide, and means whereby each retracting cam when leading will yield so as not to retract the needles.

5. In a straight knitting machine, in combination, the needles, the needle cam slide, the retracting cams on said slide, each retracting cam having a pointed end which retracts each needle to the maximum when forming the loop, and means whereby each pointed end will yield so as not to retract the needles, when its cam is leading.

6. In a straight knitting machine, in combination, the needles, the needle cam slide, the stitch-forming cams on each slide including the retracting cams, means for changing the tension by adjusting both retracting cams to a set position in which one cam is operative during the forward stroke and the other during the back stroke, and means whereby each retracting cam will be moved from its said set position when leading so as not to stress the held loops.

35 7. In a straight knitting machine, in combination, the needles, the needle cam slide, the stitch forming cams on each slide including the retracting cams, means for shifting the retracting cams to knit a slack course, and means whereby each retracting cam when leading will yield so as not to impose additional tension on the held loops.

45 8. In a straight knitting machine, in combination, the needles, the needle cam slide, the stitch-forming cams on the slide including the retracting cams, each retracting cam having a pointed end for completing the stitch, and means whereby said pointed ends of the retracting cams will be rendered 50 inoperative by yielding so as not to retract the needles when such cams are in the leading position during any stroke.

55 9. In a straight knitting machine, in combination, the needles, the needle cam slide, the stitch-forming cams including the retracting cams, each being movable in the plane of its needle-retracting face for changing the tension of the knitting and having an independent yielding movement 60 when leading so as not to stress the held loops.

65 10. In a straight knitting machine, in combination, the needles, the needle cam slide, the stitch-forming cams, the retracting cams each being movable in the plane

of its needle-retracting face for changing the tension of the knitting and having an independent movement when leading so as not to stress the held loops, tension-adjusting means adapted for holding the retracting cams in working position and means yieldingly opposing said independent movement of the respective retracting cams and for returning them to said working position.

70 11. Needle-operating mechanism for straight knitting machines including, in combination, means whereby each needle-retracting cam when leading will yield by contact with the needle-actuating lugs so as not to stress the held loops, and filler springs imposing less pressure on the needles than is required in the absence of the first-mentioned means.

75 12. Needle-operating mechanism for straight knitting machines including, in combination, retracting cams, means whereby each needle-retracting cam will be moved from its normal operative position when leading so as not to stress the held loops, and filler springs imposing less pressure on the needles than is required to prevent premature advancing of the needles in the absence of the first-mentioned means.

80 13. In a straight knitting machine the combination with the needles and a cam slide having needle-retracting cams and an advancing cam, of light filler springs for imposing such light pressure on the needles as to permit each needle to be advanced under the yarn pull or tension immediately after being moved by its retracting cam to the final loop drawing position, a projection on each retracting cam allowing each needle to be so advanced, and means whereby each retracting cam will yield when leading so as not to stress the held loops and whereby such retracting cam will not act on the needles so as to cause premature advancement thereof.

85 110 14. Needle-operating mechanism for straight knitting machines, including needle-retracting cams and an advancing cam, means whereby each retracting cam will be displaced from its normal operative position when leading so as not to affect the normal position of the needles, and means for imposing comparatively light pressure on the needles permitting each needle to be advanced under the yarn pull immediately after its loop is drawn to the fullest extent by the retracting cam, the displacing of said leading retracting cam eliminating any such action on the needles as to cause premature advancement thereof especially with lighter needle pressure.

115 120 125 130 15. Needle-operating mechanism for straight knitting machines including needle-retracting cams, and means whereby each retracting cam when leading will be dis-

placed from its normal operative position so as not to stress the held loops, independently of displacement of the other retracting cam from its normal operative position.

5 16. In a straight knitting machine, in combination, a cam slide, a cam, and a mounting for the cam on the slide comprising a rebated and tongued bearing joint.

10 17. In a straight knitting machine, in combination, a cam slide, a cam, and a mounting for the cam on the slide comprising a rebated and tongued bearing joint having end bearing faces and an intermediate bearing face in parallel planes transverse

15 to the pressure strains on the cam.

18. In a straight knitting machine, in combination, the needle cam slide, the needle retracting cams, a sectional carrier for each cam, tension-changing means attached to one 20 of the carrier sections for each cam, and a spring for holding the carrier sections for each together and permitting relative movement between said sections.

19. In a straight knitting machine, in combination, the needles, a cam slide, stitch-forming cams on each slide, a sectional carrier for the retracting cam, one of the carrier sections being movable with respect to the other and carrying the retracting cam, 30 and a spring yieldingly holding the carrier sections together and permitting relative movement therebetween.

20. Needle-operating mechanism for straight knitting machines including, in combination, a cam slide, needle-retracting cams, a sectional carrier for each retracting cam, one section of each carrier being slidable on the cam slide in a plane parallel with the needle retracting face of its 35 retracting cam, means connected with both slidable carrier sections for adjusting them to vary the tension, each retracting cam being fixed to the other carrier section which

latter is movable in said plane toward and from its first-mentioned carrier section, and a spring acting against each retracting cam to hold it in its normal operative position and permit it to yield therefrom when leading so as not to stress the held loops.

21. Needle-operating mechanism for straight knitting machines comprising in combination with the needles, of a cam slide, needle-retracting cams and an advancing cam, each retracting cam having a pointed end adapted for drawing the needles down to the final position when forming the loop to allow the needles to advance slightly to a determined position after drawing the loop, and means for causing each retracting cam when leading to be displaced from its normal position so as to not stress the held loops, said displacing movement taking place independently of movement of the other retracting cam and while it is in its normal operative position for retracting the needles.

22. Needle-operating mechanism for straight knitting machines comprising, a cam slide, needle-retracting cams and an advancing cam on said slide, a sectional carrier for each retracting cam, the retracting cam being fixed to one of the carrier sections, the other carrier section having means extending through the cam slide and adapted to be adjusted for varying the tension, means mounting both carrier sections on the cam slide so that they are movable in a plane parallel with the needle-retracting face of the retracting cam, means connected with the carrier adjusting means for each retracting cam for simultaneously moving said cams to increase or decrease the tension, and means whereby each retracting cam when leading will be displaced so as not to impose additional tension on the held loops.

WALTER F. ROLSTON.
